WALLACE B. VAN ARSDEL, OF BERLIN, NEW HAMPSHIRE, ASSIGNOR TO BROWN COMPANY, OF BERLIN, NEW HAMPSHIRE, A CORPORATION OF MAINE

APPARATUS FOR PRODUCING NITROGEN

Application filed November 10, 1921. Serial No. 514,191.

This invention relates to apparatus for the production of nitrogen by the combustion of hydrogen in air and the removal of the products of combustion from the residual gas.

More particularly this invention is concerned with means for supplying a constant and regulable amount of air and hydrogen to a combustion furnace, and safety devices for minimizing the danger of explosions or of producing a gas which either forms an explosive mixture with air or contains an excess of air. These and other features of the invention will appear from a more complete description of an illustrative embodiment thereof disclosed in the accompanying drawings in which

Figure 1 is a diagrammatic view of the apparatus.

Figure 2 is a side elevation partly in section of the furnace.

Figure 3 is an end view thereof.

Figure 4 is a partial plan of the gasometers.

Figure 5 is a front elevation thereof.

Figures 6 and 7 are front and side detail elevations of the gasometers and motor regulating devices.

The flow of a gas in practice is always regulated by making use of a drop in pressure across some sort of resistance, an increase in flow being accomplished by either lowering the resistance while keeping the pressure difference constant or increasing the pressure difference while the resistance is held constant, or by combinations of the two methods.

In the present instance as the air and hydrogen are mixed in the combustion furnace the outlet pressures of the gases are equal, though variable dependent on the use to be made of the gas. As it is quite abnormal

that the ratio of the hydrogen to the air shall be kept constant so as to permit complete combustion without undue excess of either hydrogen or air in the final product, it is essential that the initial pressures and the resistances be closely regulated. As the final pressure may vary somewhat, as before stated, it therefore becomes important that the initial pressure shall be somewhat high and the resistances large to cause the drop in

pressure to be considerable in order that

slight variations in the final pressure may have an inconsiderable effect on the total drop. It is also essential that the initial pressures be held closely constant. In order to so hold these initial pressures, weighted gasometers have been employed, since it is evident that pumps alone will not give sufficiently constant pressure. In order that the resistances may be considerable to effect a marked decrease in pressure and yet be dependable, a long series of pipes of greater than capillary diameter are employed. These pipes should be of material not substantially corroded by any of the constituents of the gas, brass having been found satisfactory in practice. Resistances to the flow of gases are often composed of constrictions or orifices, in the line. Such constructions to accomplish the large decrease in pressure here desired would need to be of an extreme type, the orifice being merely a pin hole, or the constriction a capillary. As such constructions are liable to change in resistance owing to corrosion or sudden complete plugging by a comparatively small particle of solid material, they are evidently not suited to the present purposes.

Referring then to Figure 1 the apparatus comprises a pair of air and hydrogen pumps shown at 1 and 2 both of which are belt connected to a driving motor 3. From each pump the gas passes through a cooling tank 4 for condensing out moisture and then through a separator 5 in the air line and a similar separator 6 in the hydrogen line, preferably of the baffle type, to remove suspended droplets of moisture. From there the gases pass through the bag filters 7 and 8 to remove particles of solid matter or oil which might be in suspension, and through regulating valves 9 and 10 to air and hydrogen gasometers 11 and 12. From the gasometer 11 the air passes through a system of pipes 13 forming the resistance element and through a pipe 14 to the combustion furnace at 15. The hydrogen passes from the gasometer 12 through the resistance piping 16 and the pipe 17 to the furnace. The size and length of the resistance piping are, of course, dependent on the capacity of the plant and the pressure drop

desired—the smaller the volume of gas required, the longer the piping of a given size, or the smaller the piping of a given length for equal pressure drop. Preferably piping about $\frac{1}{8}$ inch in diameter would be about the smallest size successful in order that capillary effects might not be noticeable.

This furnace is shown in detail in Figures 2 and 3 and comprises a casing 18 lined with an insulating medium such as magnesia and fire brick 19 leaving a longitudinal passage for combustion at the center. This space is preferably partly filled with pieces of fire brick as 20 to increase the refractory surface. The air and hydrogen are conveniently supplied to this furnace through concentric pipes 21 and 22 passing through a flange 24 which may be bolted by a plurality of bolts 25 having pivotal connection with a flange 26 fast to the end plate 27 of the casing 18. The hydrogen pipe 17 is connected to the inner pipe 22, and the air pipe 14 is connected to the outer pipe 21. The inner end of these pipes 21 and 22 terminates in a combustion nozzle 27 which extends within the combustion chamber when the flanges 24 and 26 are bolted together. For convenience in lighting, the pipes 21 and 22 are connected by flexible tubing with the pipes 14 and 17 so that the combustion nozzle 27 may be withdrawn from the furnace, a small plug cock as 30 and 31 being provided in each line to adjust the quantity of gas initially. On starting up after the gasometers are full and hydrogen has run from the nozzle until tests show it free of oxygen, the hydrogen plug cock is partly closed so that the gas may be safely lighted, and the nozzle is then inserted in the furnace, the flanges bolted, and both plug cocks opened wide. This procedure eliminates the danger of an explosion in the furnace on starting the apparatus.

The hot mixture of nitrogen and superheated water vapor in the furnace may then be cooled and the water removed so that the nitrogen may be utilized. This cooling and separating out of the water may be carried out, in stages, as shown in Figure 1, an air cooler 35 being first employed, then a water cooler 50 36, a baffle separator 37 for removing the droplets of water, and finally, if desired, refrigerated brine in duplicate coolers 38, one of these coolers being operated while the incrustations of ice are removed from the other. At this point the gas may be tested and upon excess of either oxygen or hydrogen being shown adjustments may be made in the apparatus. It is found convenient to make preliminary rough adjustments in the resistances 60 by varying the length of piping through which the gases flow. Fine adjustments are then determined by varying the weight applied to the gasometer bells, it being desirable to maintain these weights as nearly equal as possible to impart equal initial pressures, in

view of the fact that the final pressures of the gases as they are mixed are equal. The resistance elements are preferably composed of a series of pipes joined at their ends by cross connections 40 which have removable plugs opposite the ends of the pipes so that access may be had by a cleaning rod in order that the interiors of the pipes may be periodically and readily cleaned.

The pressure which may be successfully applied to gases by means of gasometers is limited by the available height of the gasometer tank since this pressure is balanced by the head of the sealing liquid. It has been found in practice that pressure of two pounds is sufficient in this apparatus, the gasometer bells being immersed in non-aqueous liquid such as oil which not only serves to prevent admission of moisture to the gas but also serve to lubricate the rollers carried by the gasometer bells and which engage the inner faces of the tanks. By this means the rollers are always kept in free running condition and failure of the gasometers to freely function is reduced to the minimum.

It is desirable that the pumps shall be able to pump the gas at somewhat higher pressure into these gasometers, particularly in view of the resistances interposed in the shape of the apparatus for removing water, dust, and so forth. For this purpose the pumps may be designed to operate at, say, four pounds per square inch, it being preferable to provide safety valves at the outlet side of these pumps in order to prevent an excess pressure being supplied. Such valves are indicated on Figure 1 at 45 and 46, the valve 45 for the air line preferably exhausting into the atmosphere and the valve 46 for the hydrogen line preferably exhausting through the pipe 47 into the pump intake. This construction provides ample pressures of the gases while insuring against excessive pressures.

In order to provide against an accidental disablement of one of the pumps resulting in excess of the gas delivered by the other pump, both these pumps are driven from a common motor, the control switch therefor being positioned at 48 adjacent the gasometers. Means are then provided by which the lowering of either gasometer bell to a certain point serves to open this switch stopping the operation of the motor. This mechanism is shown in detail in Figures 4, 5, 6, and 7. As shown the upper end of each gasometer bell terminates in a flange 50 within which is a space for the reception of sectoral weights 51 (see Figure 4) by which the pressure exerted on the gas by these bells may be regulated. Centrally of this flange is pivoted to the upper end of the bell an arm 52 to the upper end of which is pivoted a lever 53. Both these levers are pivoted to a collar 54 fixed to a post 55 extending upwardly from a frame 56 which supports the gasometers.

Depending from the levers 53 between their ends are rods 156 having rack portions 57. To the lower end of each bar is pivoted a pair of links 58 as shown in Figures 6 and 7 preferably having turnbuckles 59 intermediate thereof for adjusting their lengths. These links 58 terminate in slotted lower extremities 60 through which are passed pivots 61 carried at opposite ends of an arm 62 fixed to a rock shaft 63 journaled at 64 in the supporting frame. As shown in Figure 7 the rear arm 58 is considerably shorter than the forward arm so that in the position shown the pivot 61 bears toward the lower end of the rear arm and toward the upper end of the slot in the forward arm. By this construction, if the gasometer bell lowers sufficiently, the forward pivot 61 is engaged by the upper end of the slot on the corresponding link, 20 rocking the forward end of the arm 62 downwardly. If the gasometer bell rises sufficiently, the rear pivot 61 is engaged by the lower end of the slot in the corresponding arm 58, the rear end of rock arm 62 being 25 raised. It is therefore seen that by movement of the gasometer bell, either upwardly or downwardly beyond determined points the rock shaft 63 is rocked in the same direction.

Pivoted above the switch 48 at 65 is a lever 30 66 having a slotted rear end 67 taking over one of the pivot pins 61. Forwardly of the pivot 65 this lever carries a depending arm 68 terminating in a hook 69. In the normal nearly horizontal position of the lever 66 this 35 hook 69 extends beneath the switch tripping finger 70 which is depressed to substantially the position shown in Figure 7 when the switch 48 controlling the motor 3 is closed. It is therefore evident that when the rock 40 shaft 63 is rocked by either too great an ascent or descent of either of the gasometer bells, the outer end of the lever 66 is swung upwardly and the hook 69 engaging beneath the finger 70 moves the switch to the off position. When the apparatus is first started, 45 it is evident that the bells are at their downward limit of motion, this causing the hook 69 to be in its raised position so as normally to hold the switch open and prevent the starting of the apparatus. The arm 68 may be 50 swung outwardly from beneath the finger 70 by the operator and the finger may then be thrown down and the apparatus started. As the gasometer bells rise lever 66 may be depressed by actuation of handle 66^a, the hook 69 riding over the outer face of the finger and swinging thereunder as the inner end of the lever strikes the stop pin 84 whereupon 55 the safety appliance automatically assumes its operative position. With this construction should either one of the pumps fail allowing its gasometer to fall, the motor is stopped when the gasometer bell has reached 60 a predetermined position, while should either

of the bells rise too far the motor is stopped in the same manner.

Provision is also made for controlling the valves 9 and 10 by the position of the gasometer bells so that gas may be supplied from the pumps only as fast as it is utilized. For this purpose each rack bar 57 engages a gear 75 journaled on the supporting frame, this gear having fixed thereto a cam 76. This cam has its periphery formed as a pair of concentric arcs 77 and 78 of different diameters joined by inclinations 79. Cooperating with this cam is a follower comprising a yoke member 80 having thereon rolls 81 and 82 extending on diametrically opposite sides of the 80 cam 76. The lower end of this yoke 80 is attached to the valve stem 83 of the regulating valve. The position of the cam 76 shown in Figure 7 is the one it assumes when the gasometer bell is at downward limit of motion. When the apparatus is put into operation, the bell rises and the cam 76 turns correspondingly until the rollers 81, 82 ride on the inclinations 79, at which time the bell is in normal operating position. From this 85 position any slight rise of the bell will move the cam face 77 nearer the roller 82 and will thus force the valve stem 83 downward. A lowering of the bell will move the cam 90 face 77 nearer the roller 81 and will thus force the valve stem 83 to rise. These parts are so designed that as the gasometer bell lowers the valve is opened and as it rises the valve is closed, motion of the valve taking place 95 entirely within a comparatively small amplitude of motion of the gasometer bell at either limit of the desirable motion thereof. Should either of these valves fail to function and the corresponding bell travel either 100 too high or too low the supply of gas thereto is stopped in ample time to avoid trouble by the action of the switch mechanism before 105 described.

It has been found that with an apparatus of this description supplies of gas may be 110 furnished to the furnace sufficiently accurately to require little attention and to permit only slight changes in the constituents of the final gas.

While this apparatus has been described 115 in connection with the production of nitrogen by the combustion of hydrogen in air, it is evident that means for regulating the flow of a plurality of any gases which it is necessary or desirable should take place in balanced ratio might employ features of this 120 invention.

An embodiment of this invention having thus been described it should be evident that many changes and modifications might be 125 made therein without departing from its spirit or scope as defined by the appended claims.

I claim:

1. In an apparatus of the class described, 130

a plurality of gas pumps, a common motor for actuating said pumps, a gasometer for receiving the gas from each pump, and manually reset means actuated by abnormal movement of any gasometer for stopping said motor.

2. In an apparatus of the class described, a pump, a motor for actuating said pump, a gasometer for receiving gas from said pump, and means for stopping said motor upon movement of the bell of said gasometer beyond a predetermined distance in either direction from normal operating position.

3. In an apparatus of the class described, a gas pump, a motor for actuating said pump, a pressure regulator receiving gas from said pump and containing a predetermined volume of gas under normal operating conditions, and means actuated by excessive variation from the normal volume of gas in either direction in said pressure regulator for stopping said motor.

4. In an apparatus of the class described, a plurality of gas pumps, an electric motor for actuating said pumps, a switch for controlling said motor, a gasometer for receiving gas from each of said pumps, and manually reset means actuated by abnormal movement of the bell of any of said gasometers for opening said switch.

5. In an apparatus of the class described, a plurality of gas pumps, a single electric motor for actuating all said pumps, a switch for controlling said motor, a gasometer for receiving gas from each of said pumps, and means actuated when the bell of any of said gasometers either rises or falls to predetermined points for opening said switch.

6. An apparatus of the class described comprising a pump, an electric motor for driving said pump, a gasometer for receiving gas from said pump, a starting switch for said motor mounted adjacent said gasometer, a rock shaft, a two-armed lever fixed to said shaft, lost motion connections from the bell of said gasometer to opposite ends of said lever, whereby raising or lowering of said gasometer bell beyond determined points rocks said shaft in one direction, and a connection from said shaft acting to trip said control switch when said shaft is rocked by either of said lost motion connections.

7. In an apparatus of the class described, a pump, a gasometer, a valve interposed between said pump and gasometer, and means actuated by the movement of the bell of said gasometer for controlling said valve.

8. In an apparatus of the class described, a pump, means for driving said pump, a gasometer, and connections from the bell of said gasometer for rendering inoperative said driving means on abnormal movement of said bell in either direction.

9. In apparatus of the class described, a plurality of gas pumps, an electric motor for

driving said pumps, a switch for controlling said motor, a gasometer for receiving gas from each of said pumps, means actuated when the bell of any of said gasometers either rises or falls to predetermined points for opening said switch, and means whereby said switch-opening device may be held inoperative during the initial period of filling the gasometers.

10. In an apparatus of the class described, a plurality of gas pumps, means for driving said pumps, a pressure regulator to receive each gas, a valve between each of said pumps and its pressure regulator, means operated by volume of said regulators for controlling said valves, and means operated by variation of volume of any of said regulators beyond predetermined limits for rendering inoperative said driving means.

In testimony whereof I have affixed my signature.
